UNITED STATES PATENT OFFICE.

GEORGE L. PIERCE, OF BROOKLYN, NEW YORK, ASSIGNOR TO A. G. SPALDING & BROS.,
OF NEW YORK, N. Y., A CORPORATION OF NEW JERSEY.

SHOE.

Application filed March 25, 1924. Serial No. 701,763.

To all whom it may concern:

Be it known that I, GEORGE L. PIERCE, a citizen of the United States, and a resident of Brooklyn, in the county of Kings and State of New York, have invented certain new and useful Improvements in Shoes, of which the following is a specification.

My present invention relates to improvements in shoes and is intended more especially for embodiment in a bathing shoe, though not limited to this specific article of footwear.

The invention aims to provide a shoe of this character which can be economically manufactured, which will have a light non-slipping outsole capable of withstanding wear and protecting the foot of the wearer from rocks and the like, which outsole will be united to the shoe in a permanent manner, and in which the lower edge of the upper will be united to the shoe in a permanent manner, and in which the lower edge of the upper will be provided with a protecting strip, and the seam uniting the parts will be protected from sand and rough places traversed by the wearer.

With these and other objects in view, the invention includes the novel features of construction and arrangement and combination of parts hereinafter described and particularly defined by the appended claims.

What I at present consider the preferred embodiment of my invention is illustrated in the accompanying drawings, in which:

Fig. 1 is a sectional elevation of a cloth or canvas shoe having a rubber sole.

Fig. 2 is a sectional detail on a larger scale.

Fig. 3 is a sectional detail illustrating a step in the manufacture.

Referring by reference characters to this drawing, the numeral 1 designates the cloth or canvas upper which in the present instance is provided with heel and edge reinforcements 1^a and 1^b and toe cap 1^c suitably stitched thereto, and 2 the cloth insole which is united to the upper by an out-turned seam, indicated at 2^a. 3 designates an intermediate sole member comprising relatively heavy textile material of the character known as friction fabric, having one face (the lower) 3^a preferably skim coated with rubber compound, but both surfaces being of a sticky

or tacky nature. This latter is cut flat from a suitable sheet and has connected to its marginal edge by through and through stitches 4^a a strip of suitable fabric material, such as duck, canvas or the like, and a leather strip 5 in the order named, the stitching being done when the sole member 3 is in a flat condition, as illustrated in Fig. 3, the skim coated surface of the sole member 3 being preferably covered by a removable glazed protecting sheet 6 of slightly less area than the sole member to prevent the fabric strip 4 adhering to the sole during manipulation and stitching.

The surface 3^b of the sole 2 is then pressed firmly against the outer surface of the insole 2 and caused to adhere thereto by its tacky nature, and the leather strip 5 is turned up around the lower edge of the upper and secured thereto conveniently by having its edge stitched thereto by a line of stitches indicated at 5^a.

The glazed protecting strip 6 is now removed and an outsole 7 of suitable material, such as crêpe rubber, is applied to and pressed firmly against the skim coated rubber surface of sole member 3 and caused to firmly adhere thereto, whereafter the fabric strip 4 is turned down and firmly cemented to the edge of the outsole, as clearly shown in Fig. 2. By this arrangement the outsole is firmly secured to the intermediate sole 8^a and all danger of separation at the edge removed, while the composite sole thus formed and the marginal strips are firmly united together and to the upper, leaving no exposed stitches at the junction of the sole and the upper.

While I have described the intermediate sole of rubberized fabric in a tacky condition, it is obvious that it could be made of any suitable material and cement used for connecting the parts in place of the tacky nature of the rubber. When unvulcanized rubber is used, the shoe may be subjected to vulcanizing heat to cure the rubber compound and cause a more perfect union.

It will also be obvious that while I have described a canvas shoe as the specific embodiment of my invention, I do not limit myself to the use of any particular material, as any or all parts of the shoe may be made of any suitable material, according to

the uses to which the shoe is to be put, without departing from the spirit of my invention.

Having thus described my invention, what I claim is:

1. A shoe of the character described comprising an intermediate sole, an outsole adhering to one face thereof within the margins thereof, an upper having an insole adhering to the other face of the intermediate sole, and a pair of strips stitched to the margin of said intermediate sole, one of said strips being turned up and secured to the upper and the other being turned down over and secured to the edge of the outsole.
2. A shoe of the character described comprising an upper having a sole portion forming an insole, an intermediate sole having a pair of superposed strips secured to the margin thereof, said intermediate sole being juxtaposed to the insole and having its margin turned up, and an outsole applied to the exposed face of the intermediate sole, one of said strips being turned up and secured to the upper and the other turned down and secured to the edge of the outsole.

3. A shoe of the character described comprising an upper having a sole portion forming an insole, an intermediate sole overlying said insole, an outsole adhesively secured to the exposed face of said intermediate sole, a pair of strips having superposed edges secured to the margin of said intermediate sole by an inturned seam, one of said strips being turned up over and secured to the upper and the other being turned down over and secured to the edge of the outsole.

4. A shoe of the character described comprising an upper having a sole portion forming an insole, an intermediate sole overlying said insole, an outsole adhesively secured to the exposed face of said intermediate sole, a pair of strips having superposed edges secured to the margin of said intermediate sole by an inturned seam, one of said strips being turned up over and stitched to the upper, and the other being turned down and cemented to the edge of the sole.

In testimony whereof, I affix my signature.

GEORGE L. PIERCE.
